UNITED STATES PATENT OFFICE.

LOUIS H. ORR, OF NEW YORK, N. Y.

PROCESS FOR PARTIALLY SIMULATING HAND-MADE PAPER.

1,299,216.

Specification of Letters Patent.

Patented Apr. 1, 1919.

Application filed January 3, 1916. Serial No. 70,058.

To all whom it may concern:

Be it known that I, LOUIS H. ORR, citizen of the United States, and resident of the city of New York, in the county of New York and State of New York, have invented certain new and useful Processes for Partially Simulating Hand-Made Paper, of which the following is a specification.

My invention relates to a process for producing textile effects on paper surfaces, and has for an object to approximate an imitation of certain types of hand made paper.

In the class of paper products referred to, among which for example is the so-called Japanese hand made paper, there is seen a distinctive, material feature, because it is formed in such manner that upon the surface thereof appear what I shall designate as spots or patches of the fibers that existed in the materials from which the paper is made. In these papers the resulting designs of such fibrous portions are of irregular shape and arrangement, appearing in more or less general uniformity upon the surface to produce a peculiar flecked or dappled effect, present in the aforesaid style of paper. While the strands of fiber appear in varying forms and figures, as pointed out, in each individual patch there is a tendency toward approximate parallel arrangement of the fiber. Likewise, the strands in one patch may run at right angles to the prevailing direction of those of an adjacent group, or in a direction slightly varying relatively thereto, or it may be the strands are in the same general arrangement. Furthermore, there may be an entire absence of fibrous appearance between the fiber marked portions, and the strands of one group may seem to disappear under the threads of an adjacent area, the direction of the individual fibers, however, varying apparently according to no fixed rule.

My process therefore may in general terms be described as consisting in reproducing a printed sheet simulating the peculiar surface effect of the hand made paper of the type described, having reference especially to the said Japanese variety thereof.

Having reference to the drawings:

Figure 1 in diagrammatic form represents the successive steps followed in attaining the result of my process.

Fig. 2 represents the face of a sheet of paper produced in the preliminary steps of the process.

The numeral 1 represents a surface showing the effect produced in the first stages of my process. 2 is a representation of individual fiber strands as they appear at the surface of a hand made paper, forming areas of fibrous appearance, which I have termed the fiber patches 3. In like manner the numeral 4 marks similar areas intermediate the fibrous patches 3 where brushes of whitish coloring are laid on so as to slightly overlap 60 surrounding portions of fibrous sections. In carrying out my invention, therefore, as a first step to this end, I trace upon a sheet of light color in dark lines, such as those marked with commercial india ink, groups 70 of fine lines 2 designed to resemble more or less closely the fiber strands which constitute the aforementioned fibrous areas, such for example as characterize the said Japanese hand made paper above mentioned. 75 These markings are made to follow similar diversity of direction and arrangement generally as appears in the paper of which an imitation is sought to be made by my process. This may be conveniently and 80 most satisfactorily accomplished by selecting a sample of the paper thus to be simulated and tracing ink lines along typical fiber threads that distinguish the so-called patches above attended to. 85

I then spread upon the sheet prepared in the manner above described in irregular brushes of Chinese white or other light tinted colors the flecked areas 4 with the same general arrangement and irregularity as the 90 original patches 3, but adapted primarily to cover the intervening spaces between the aforesaid patches of fibrous reproductions. The dashes of wash color are preferably made of Chinese white and slightly overlap 95 the edges of the fibrous drawn patches so as to blend the ends of the lines or markings representing the fiber strands in such manner as to suggest the disappearance of the end of the natural fiber into the surface in 100 the diversified manner above referred to.

I then reproduce by the photographic process, in the form of the well known half tone plate, the result of the preceding steps in which the black lines representing fiber 105 lines are rendered somewhat less distinctive in having been thus reproduced in the form of a half tone plate, and then as a final step I imprint with printers' ink upon a suitably selected paper surface the half tone thus 110

produced, over which may be spread any desired tint or color by means of a printer's tint block, which permits the effect of the half tone thus prepared and produced to become visible through the outer coating of thin material, wherein the black lines of the fiber are still further rendered less clearly marked or defined. The result thus obtained by the several steps as given, is to produce a pleasing effect suggestive of the hand-made paper of the type described, but which has an esthetic value of its own.

Having described my invention, what I claim is:

15. The within described process, which consists in, first, placing upon a sheet of light color dark lines representative of fiber patches in certain kinds of paper; then laying on brushes of white wash colors intermediate said fibrous patches and slightly overlapping the edges thereof; then making a half tone plate thereof by photographic

process; finally making an impression upon suitable paper by said photo plate.

2. The within described process, which consists in, first, placing upon a sheet of light color dark lines representative of fiber patches in certain kinds of paper; then laying on brushes of white wash colors intermediate said fibrous patches and slightly overlapping the edges thereof; then making a half tone plate thereof by photographic process; making an impression upon suitable paper by said photo plate; then overlaying said impression in black ink with a tint or color as desired.

Signed at the city of New York, in the county of New York and State of New York.

LOUIS H. ORR.
